UNITED STATES PATENT OFFICE.

ROSS L. HAUGH AND WILLIAM G. HAUGH, OF CLEVELAND, OHIO.

LINOEUM-STRETCHER.

1,143,965.

Specification of Letters Patent. Patented Aug. 3, 1915.

Application filed January 12, 1914. Serial No. 812,439.

To all whom it may concern:

Be it known that we, ROSS L. HAUGH and WILLIAM G. HAUGH, citizens of the United States, residents of Cleveland, county of Cuyahoga, and State of Ohio, have invented a new and useful Improvement in Linoleum-Stretchers, of which the following is a specification, the principle of the invention being herein explained and the best mode in which we have contemplated applying that principle, so as to distinguish it from other inventions.

Our invention relates to linoleum stretchers, its object being to provide a linoleum stretcher which will be simple in construction, economical of manufacture, which may be readily applied and which will be efficient in its use.

As compared with carpet, linoleum is very difficult to stretch, for the reason that the ordinary carpet stretcher is not capable of gripping the linoleum with sufficient force and furthermore the stiffness of linoleum requires the application of greater force to properly lay it without marking or defacing the surface of the linoleum.

The said invention consists of means hereinafter fully described and particularly set forth in the claims.

50 The annexed drawing and the following description set forth in detail certain means embodying our invention, the disclosed means, however, constituting but one of various mechanical forms in which the principles of the invention may be applied.

In said annexed drawing:—Figure 1 represents a plan of a stretcher embodying our invention, showing a piece of linoleum placed therein. Fig. 2 represents a side elevation of the said stretcher also showing the piece of linoleum placed therein. Fig. 3 represents a side elevation of a modified form of stretcher embodying part of the principles of our invention.

55 The invention as illustrated by Figs. 1 and 2 comprises a base-member 1 provided at its rear portion with two prongs 2, 2, the latter being adapted to engage the floor. This base-member extends forwardly and is provided with an upwardly and rearwardly extending front curved portion 3. To this front portion 3 of the base-member is pivotally secured the front end of a clamping-member 4, such end being downwardly and rearwardly curved and terminating in an extension 5 forming the handle which is

provided with a suitable grip 6. It will therefore be seen that the clamping-member 4 may be oscillated so as to clamp between opposing surfaces thereof a portion of the linoleum 7 and very firmly secure same without marring its surface. At a place opposite that portion of the member 4 which engages the linoleum and in the upper surface of the base-member 1 is sometimes formed a transverse groove 8 although the latter is not indispensable. Where the groove 8 is used, the depression of the clamping-members pinches the linoleum, and forces a portion of the linoleum into this groove and assists in securing same in the stretcher as will be readily understood.

Formed on the central part of the portion 3 of the base-member is a succession of ratchet teeth 9 which may be engaged by an oscillatory pawl 10 pivotally mounted upon the handle 5. By means of this ratchet and pawl it will be seen that the angular relation of the clamping and base-members may be fixed if desired. It will also be noted that the form of the clamping-member is such that when the parts are in their clamping position the handle of the clamping-member will extend at an angle with respect to the base-member 1. This, as will be readily understood, permits linoleum of varying thickness to be securely clamped, no matter how small in thickness they may be.

In applying the above described device, the pawl 10 is first disengaged from the ratchet teeth 9 and the handle carried upwardly so as to permit the linoleum to be placed between the clamping-member and the base-member. The pawl is then thrown over onto the portion 3 and the prongs 2 caused to engage the floor. The handle is then depressed so as to securely clamp the linoleum, the pawl 10 engaging one of the ratchet teeth to hold the two parts in clamping position. By now bearing down upon the forward end of the base-member, it will be seen that the linoleum may be stretched as desired. After the latter has been secured by means of tacks or otherwise, the said forward end may then be raised which will permit the pawl to be disengaged from the ratchet teeth.

The modified structure shown in Fig. 3 provides for a similar base-member 1 in which, however, the upwardly and rearwardly extending portion is omitted. To the forward end of this member is secured

the clamping-member 4 which is however provided with a forwardly and downwardly curved extension 11, the lower and rear end of which is pivotally secured to the base-member 1. A groove 8 is provided which is similar to that of the first-described structure. In this form the ratchet and pawl are also omitted.

The application of this last described device is similar to that of the first described device but requires a continued pressure upon the handle while the forward end of the device is being depressed to stretch the linoleum, as will be readily understood by those skilled in the art.

We have found the above described arrangement of parts to be especially useful and efficient in connection with stretching linoleum principally for the reason that, as will be readily seen, the linoleum may be very securely held between the base and clamping-members without marring or defacing its surface, and the necessary force may therefore be applied to properly lay same upon the floor. It will be understood, however, that the device may also be advantageously used as a carpet stretcher.

Having fully described our invention, what we claim and desire to secure by Letters Patent is:—

1. A linoleum-stretcher comprising the combination of a base-member provided with prongs adapted to engage the floor; a clamping-member pivotally mounted upon said base-member and adapted to secure the linoleum between it and said base-member; and a ratchet and pawl adapted to fix the angular relation of said two members.

2. A linoleum-stretcher comprising the combination of a base-member provided with prongs adapted to engage the floor and with ratchet teeth; a clamping-member pivotally mounted upon said base-member and adapted to secure the linoleum between it and said base-member; and a pawl mount-

ed upon said clamping-member and adapted to engage said ratchet teeth.

3. A linoleum-stretcher comprising the combination with a base-member having downwardly projecting prongs for engaging the floor and an upwardly and rearwardly extending front portion; of a clamping-member having its forward end pivotally secured upon the rear extremity of said front portion; said forward end being upwardly and rearwardly curved and terminating in an extension forming a handle; the latter being angularly related to the base portion when they are in their clamping position.

4. A linoleum stretcher comprising the combination with a base member provided with a prong at its inner end adapted to engage the floor; of a clamping member pivoted to the outer end of said base member and adapted to secure the linoleum between it and the latter and intermediately of said prong and its pivotal axis, said clamping member extending at an angle from said member when in its securing position.

5. A linoleum stretcher comprising the combination with a base member provided with a prong at one end adapted to engage the floor; of a clamping member pivoted to the other end of such base member and having a handle connected therewith and extending in the same general direction as said prong; said clamping member being adapted to secure the linoleum between it and the latter and intermediately of said prong and its pivotal axis, and extending at an angle from said member when in its securing position.

Signed by us, this 12th day of January, 1914.

ROSS L. HAUGH.
WILLIAM G. HAUGH.
